UNITED STATES PATENT OFFICE.

MAX ANDERS EKLOF, OF CHICAGO, ILLINOIS.

COLUMN CLAMP.

Application filed April 28, 1927. Serial No. 187,201.

My invention relates to an improved type of clamp for concrete columns. The objects of my invention are to provide a column clamp which can be quickly and conveniently assembled in clamping position about the column, which is economically manufactured, which can be conveniently folded up into substantially compact form, and which will effectively function to firmly hold the sides of the column in desired position and arrangement.

One of the main objects of my invention resides in providing an improved construction of column clamps wherein the clamping members may be moved inwardly any desired amount against the faces of the column and held firmly in such clamping position, the clamping members at the same time being arranged to maintain a predetermined relation toward each other.

These and other objects of my invention will be apparent from a perusal of the following specification when taken in connection with the accompanying drawings wherein

Figure 1 is a perspective view of my improved clamping device in position upon a column.

Figures 2 and 3 are perspective views of the block member of my clamping device.

Figure 4 is a perspective view of one of the hinged clamping members in closed position.

Figure 5 is a partial view showing the overlapping free ends of two adjacent clamping bars.

Figure 6 is a plan view of the slotted end of the clamping bar showing the two series of spaced slots arranged in overlapping relation.

Figure 7 is a modified form of a bar showing a single slot having continuously arranged overlapping slots.

Referring now to the drawings in detail, in the preferred embodiment of my invention the column clamp comprises a series of four rigid bars 2, 4, 6 and 8 preferably of metal. These bars in the form illustrated are arranged in pairs, the bars of each pair being pivoted or hinged together as at 10 and 12 so that when each pair of bars is opened into L shaped formation the two pairs of bars may be arranged as clearly shown in Figure 1 with their free extremities 14, 16, 18 and 20 in overlapping relation and enclosing the columnar frame

22. As well known in the art, these frames are generally made of rectangular shape, preferably square, and they are in the form of boards forming a square hollow into which the concrete is poured. It is absolutely necessary that these boards form a true and exact rectangle or square, and that they be firmly held in such position while the concrete is being poured and thereafter until the concrete sets. This is the function of these clamps. Each column will have several of these clamping devices arranged therein in vertical spaced-apart series. In the embodiment of my invention illustrated in the figures of the drawing I prefer to form the hinged end of a pair of bars with means for holding the bars at exactly right angles the one to the other when they are in open formation, as shown in Figure 1. 75 This is accomplished by providing the end of one of the bars with a cutout 24 and adjacent depending tongue 26, which tongue 26 is permitted to swing across the end of the connected bar by reason of the cutout and 80 will act as a stop as plainly shown in Figure 1 to hold the bars of a pair at exactly right angles when in open position.

Manifestly these bars may or may not have this stop construction as a part thereof. However, this stop construction has another important function, and that is to provide means whereby the bars of a pair can be opened only in one direction, and this is important because if the bars did not have 90 the stops thereon and were opened in the improper direction they would not allow correct overlapping relation on the column, and they would have to be removed and opened in the other direction, which would 95 be a delay. Furthermore in my improved construction wherein one bar of each pair carries the sliding block as hereinafter described if the bars of the pairs are not opened in the proper direction the two 100 blocks will be positioned on the same side or same corner of the column, which will of course make the clamp inoperative since the two blocks must be positioned at diagonally opposite corners of the column, as shown 105 clearly in Figure 1.

In the form of my invention shown in the drawings, one of the important features of my invention resides in the construction wherein the opened clamping bars when arranged as shown in Figure 1 to embrace the walls of the column the free ends of the bars

14, 16, 18 and 20 will lie perpendicular one to the other and in overlapping relation. This insures a symmetrical and exactly square or rectangular shaped clamp, the 5 sides of the bars of which will be pressed against the boards forming the hollow column. It is important that convenient and easily operable means be provided for forcibly pressing these bars inwardly against 10 the sides of the column to firmly hold the column in such position. In the form illustrated this is accomplished by providing two blocks 28 which are identical in construction. These blocks are somewhat in the 15 shape of a quarter of a circle having two sides 32 and 34 lying at right angles, the one to the other, and having an arcuate edge 36. The lateral face of the arcuate edge is opened as shown at 38, and the two faces 20 32 and 34 are provided with slots which communicate with the hollow inside of the block and with the open side 38. The slot 40 in the face 34 is not in the same plane with the slot 42 in the face 32, they being 25 spaced apart the thickness of a bar to permit the bars to pass through such slots when the bars are placed in overlapping relation as shown clearly in Figures 1 and 5 of the drawing while at the same time permitting 30 the double thickness of the two bars thus arranged in overlapping relation to pass through the open slot 38 of the arcuate face 36. This is clearly shown in the upper portion of Figure 1 of the drawings. The slot 35 40 is exactly the thickness of the bar and has its ends closed as shown in Figure 3, whereas slot 42 which is also the thickness of the bar opens into the slot 38 on the arcuate surface 36. By means of this construction the blocks 28 may be readily positioned with the overlapping bar projecting there-through as shown in Figure 1. The faces 32 and 34 of the block slant or incline rear- 40 wardly, this pitch 44 being approximately 45 one-eighth of an inch. This backward pitch is provided for cooperation with the tapering wedges as hereinafter set forth.

Each of the bars is provided with longitudinally arranged lineal holes or slots 46. In 50 the arrangement shown in Figure 6 these slots are in two series spaced apart and extending longitudinally of each bar, the slots in each series being arranged in overlapping relation, that is, the end 48 of one slot will 55 overlap the opposite end 50 of the adjacent slot of the spaced line of slots. The extent of this overlap is sufficient to permit the point of the tapering wedge 52 to be inserted a considerable distance in the over- 60 lapped slot so as to provide a sufficient lever action so that the wedge may force the block along as hereinafter described. Mani- 65 festly this overlapping arrangement may take on many different embodiments and di- 70 mensions. In the form illustrated in Figure

7 I have shown an equivalent construction wherein the single slot 54 is provided having staggeredly arranged slots joined by lateral offsets to form a continuous slot, the junction of the slots at the offsets forming the shoulder against which the tapering wedge pins may be inserted. 75

The blocks 28 are preferably mounted upon one of the bars 2 or 4 or 6 or 8 of the clamping members being held in position thereon by the stop pin 56 so that the block remains in correctly assembled position, and it is only necessary in assembling the clamping bars on the column as shown in Figure 1 to push the block inwardly so that the adjacent overlapping bars will pass through the arcuate slot 38 of the block and lie in the slot 42 of the face 32. 80

1 provide a series of wedge-shaped pins 52 for cooperation with the slots 46 for forcing the clamping bars 2, 4, 6 and 8 with any desired degree of pressure against the sides of the column. As clearly shown in Figure 1 when the clamping bars are assembled on the column they are pushed by hand firmly against the sides of the column. One of the wedge pins is then inserted in each projecting portion of a slot which extends beyond either of the side faces 32 and 34 of the block. For instance, the pin 58 in Figure 1 is shown as inserted in a portion of a slot 60, while another pin 62 is shown as being driven home in an overlapping slot in the other series on bar 2. This same operation is carried out on both faces 32 and 34 of both blocks. For instance, on the lower block as shown in Figure 1 of the drawing the pins 52 and 62 will have forced the block along both the bars 2 and 6 to a predetermined amount. Now if it be necessary to clamp the bar still more tightly against the column the pin 58 will then be inserted in the portion of the slot 60 that projects beyond the face 34 of the block, and the pin may then be driven down and the taper or wedge of the pin will then with great pressure force the block inwardly along the bar 2. In like manner another pin may be inserted in a similar projecting end of a slot on bar 6 to force the block a like distance along bar 6. In a similar manner the opposite block may be forced along the bars 4 and 8 an exact and corresponding distance. In this way the blocks will be moved equal and predetermined increments of distance along 105 the bars which will cause the bars to be forced inwardly with equal pressure against the column while maintaining the exact and true rectangular shape. Manifestly the pins hold the clamping bars in desired position. 110

It will be appreciated that the foregoing construction is very simple in manufacture, in assembly and in operation. 115 In the use of blocks a rearwardly inclined pitch 44 is provided to compensate for the 120

tapered portion 58 of the wedge shaped pins since when the pins are driven down into the slots the inclined or pitched walls 32 and 34 of the block will permit the pins 5 downward movement. This would not be permitted if the faces 32 and 34 were exactly vertical. These blocks are also made of metal and are very rugged in construction. Any desired manner of making them may 10 be availed of and may be cast and made in parts suitably held together if desired.

Having thus described my invention what I claim as new and desire to secure by Letters Patent is:

15 1. A column clamp comprising rigid bars adapted to embrace the column, blocks having sides arranged at right angles to each other and an adjoining slotted face, each of said sides having a slot therein disposed out 20 of the plane of the slot of the other side and one of said slots being continuous with the slot in the adjoining face, said sides having an inclination or backward pitch to 25 facilitate the entry of the wedge-shaped pins into the slots in the bars.

2. A column clamp comprising rigid bars pivoted together to form pairs of clamping frames, means limiting the open position of the bars of each pair to an exact right-angle, and a slotted block slidably and irremovably 30 disposed upon one of said bars, said bars having overlappingly disposed linear holes arranged longitudinally thereof for receiving wedge-shaped pins.

3. A column clamp comprising a series of 35 rigid bars arranged in pairs and pivotally connected adjacent their ends, the free end of one of said pairs of a bar having a cut-out and the free end of the other pivotally connected bar having a laterally extending lug 40 adapted to engage the side of the first mentioned bar to limit the opening movement of the pair of bars in one direction and to an exact right angle, each bar having longitudinally extending staggeredly arranged 45 openings adapted to receive wedge pins.

In witness whereof, I have hereunto subscribed my name.

MAX ANDERS EKLOF.
